SELF-LOCKING SEPARABLE FASTENER

Gale A. Rounds, Rapid City, S. Dak., assignor of
one-half to Ivan E. Landstrom, Rapid City,
S. Dak.

Application August 18, 1947, Serial No. 769,233

6 Claims. (Cl. 24—221)

1

My invention relates to clasps and has for an object to provide a clasp which may be quickly and positively assembled.

Another object of the invention resides in providing a clasp in which application of the two parts of the clasp automatically causes the same to be locked together.

Another object of the invention resides in providing a clasp having a rotatable locking member and a spring operable to rotate said locking member into locking position.

A still further object of the invention resides in providing a catch for holding the locking member in the disengaged position and in further providing releasing means operable upon assembly of the parts to release the catch.

A feature of the invention resides in providing one of the parts of the clasp with a hollow stud on which the locking member is pivoted and in disposing said spring within said stud.

Another object of the invention resides in attaching one end of said spring to said locking member and in forming on the other end of the spring into a catch for engagement with said locking member.

Another object of the invention resides in forming a trigger on said spring engageable by the other part for disengaging said catch.

Other objects of the invention reside in the novel combination and arrangement of parts and in the details of construction hereinafter illustrated and/or described.

In the drawings:

Fig. 1 is a plan view of a clasp embodying my invention, as employed on a wrist band.

Fig. 2 is a plan view of the female part of the clasp.

Fig. 3 is a plan view of the male part of the clasp.

Fig. 4 is a transverse vertical section on the line 4—4 of Fig. 1.

Fig. 5 is a view similar to Fig. 4 showing the parts prior to assembly.

Since the clasp of the present invention is of general utility, I have shown and will describe its embodiment in a wrist band 17 used for wrist watches by both men and women.

The clasp itself consists essentially of three cooperating elements—a male part 11 having an upstanding stud 12 rigid therewith, a locking member 13 pivotally mounted on the end of said stud, and a female part 14 having an opening 15 therein for the reception of the male part 11.

The male part 11 includes a base 16 which has an eyelet 10 to which one end of the wrist

2

band 17 is attached. One end of the upstanding hollow stud 12 is rigidly affixed to the base 16. A body post 18 of clover-leaf design is formed integrally with base 16 and is concentric with the stud 12. This post has lobes 34 with spaces 35 therebetween. The locking member 13 is pivotally mounted on the outer portion of the stud 12 and held in such pivotal position by means of a nut 19 which screws on the outer end of the stud 12. The locking member 13 is of the same shape and design as the post 18 and has lobes 36 and spaces 37 therebetween adapted to register with the lobes 34 and spaces 35 of post 18. A coil spring 21 is disposed within the hollow stud 12. One end of this spring extends outwardly beyond said stud and is rigidly affixed to the outer face of the locking member, by means of a projection 23 which enters a hole 24 in said locking member. The other end of spring 21 extends outwardly beyond the other end of stud 12 and is disposed in a groove 27 formed in the base 16 and post 18. This end of the spring has a catch 22 formed on the same which normally projects outwardly beyond the outermost surface of the post 18. A button 31 is rigidly affixed to the locking member 13 and provides convenient means for manually moving the locking member 13 into its trigger-engaged position wherein the clover-leaf design of the locking member 13 is aligned with the body post 18. A cover plate 25 held by screws 26 covers the bottom surface of the male member 11.

The female part 14 has an opening 15 of clover-leaf design and is provided with an eyelet 30 which is attached to the other end of the wrist band 17. The opening 15 is designed to fit snugly over the body post 18 of the male part 11 and thereby resists the mechanical forces between the two parts. The locking member 13 has a shoulder 28 adapted to be engaged by the catch 22. The coil spring is normally tensioned so as to cause rotation of the locking member 13 into the locking position whereby the female part 14 is rigidly affixed to the male part 13 as described in detail hereinbefore. The catch 22 engages a shoulder 28 to restrain movement of the locking member 13 so that the two parts may be attached or separated, as desired.

A motion limiting means is obtained by means of a pin 32 rigidly attached to the body post 18 engaging within a slot 33 in the locking member 13. Thus, the locking member 13 can only be rotated from a position where the lobes 36 and spaces 37 of locking member 13 register with the lobes 34 and spaces 35 of the post 18 to a position

in which the lobes 36 lie opposite the spaces 35.

The spring 21 has a bight 29 formed thereon which extends outwardly beyond the surface of the base 16 and serves as a trigger which is engageable by the female part 14. By pressing the female part 14 and male part 11 together, this trigger 29 releases the locking member 13 so that it rotates into the locking position.

The operation of my clasp may best be explained by going through the steps. Starting with the two parts separated, first rotate the locking member 13 on the male part 11 until the clover-leaf design registers with the same design of the body post 18. Snap catch 22 will then engage shoulder 28 and hold the two clover-leaf designed members, 13 and 18, in alignment. Then apply the opening 15 of female part 14 over the locking member 13 and the post 18. As the female part 14 engages trigger 29, the catch 22 is disengaged from shoulder 28 so that the locking member 13 is released. Locking member 13 then rotates by means of the resilient force of spring 21 to the position shown in Fig. 1 and locks the two parts in assembled relation. To separate the two parts, simply rotate the locking member 13 by means of button 31 to the trigger-engaged position wherein the clover-leaf design of the opening 15 of the female part 14 is aligned with both the post 18 and locking member 13. In this aligned position, the female part 14 is readily and easily separated from the male part 11. Thus, with very little practice or explanation, anyone can readily engage or disengage my clasp.

The advantages of my invention are manifest. It provides a new and improved clasp that has a readily detachable connection between two separable bodies or parts. It provides a positive mechanical connection between such bodies that is not dependent upon spring pressure to hold the bodies in attached relation. It is readily operable, simple and rugged in construction, light in weight, and has visible means to indicate whether the device is engaged or disengaged. A spring maintains the engaged mechanical position and a clover-leaf designed member engages the parts at all four sides. My invention is particularly useful as a clasp for jewelry and for other purposes where a quick detachable device is required for use on two cooperating bodies or parts.

Changes in the specific form of my invention, as herein described, may be made within the scope of what is claimed without departing from the spirit of my invention.

Having described my invention, what I claim as new and desire to protect by Letters Patent is:

1. A clasp comprising a male part having a base and a post extending outwardly therefrom, a female part having an opening adapted to receive said post, a hollow stud extending outwardly beyond said base, a locking member pivoted on said stud and adapted to swing from a position clearing said female part to a position overlying said female part, a spring disposed within said hollow stud and having one end engaging said locking member and the other end anchored relative to said base, said spring urging said locking member toward its latter position, a catch for holding said locking member in its former position, and releasing means operable by said female part and releasing said locking member when the post is fully received within said opening.

2. A clasp comprising a male part having a base and a post extending outwardly therefrom, a

female part having an opening adapted to receive said post, a hollow stud extending outwardly beyond said base, a locking member pivoted on said stud and adapted to swing from a position clearing said female part to a position overlying said female part, a coil spring disposed within said hollow stud and having one end engaging said locking member and the other end anchored relative to said base, said spring urging said locking member toward its latter position, a catch for holding said locking member in its former position and releasing means operable by said female part and releasing said locking member when the post is fully received within said opening.

3. A clasp comprising a male part having a base and a post extending outwardly therefrom, a female part having an opening adapted to receive said post, a hollow stud extending outwardly beyond said base, a locking member pivoted on said stud and adapted to swing from a position clearing said female part to a position overlying said female part, a spring disposed within said hollow stud and having one end engaging said locking member and the other end anchored relative to said base, said spring urging said locking member toward its latter position, a catch formed on the second named end of said spring and engaging said locking member, said catch being urged into engagement therewith through the resiliency of said spring, and releasing means operable by said female part and releasing said locking member when the post is fully received within said opening.

4. A clasp comprising a male part having a base and a post extending outwardly therefrom, a female part having an opening adapted to receive said post, a hollow stud extending outwardly beyond said base, a locking member pivoted on said stud and adapted to swing from a position clearing said female part to a position overlying said female part, a spring disposed within said hollow stud and having one end engaging said locking member and the other end anchored relative to said base, said spring urging said locking member toward its latter position, a catch formed on the second named end of said spring and engaging said locking member, said catch being urged into engagement therewith through the resiliency of said spring, and a trigger formed on the same end of said spring and engageable by said female part upon insertion of said post into said opening to disengage said catch and to release said locking member.

5. A clasp comprising a male part having a base and a post extending outwardly therefrom, a female part having an opening adapted to receive said post, a hollow stud extending outwardly beyond said base, a locking member pivoted on said stud and adapted to swing from a position clearing said female part to a position overlying said female part, a spring disposed within said hollow stud and having one end engaging said locking member, a groove formed in said base, the other end of said spring being received in said groove and being anchored thereby, a catch formed on the second named end of said spring and engaging said locking member, said catch being urged into engagement therewith through the resiliency of said spring, and releasing means operable by said female part and releasing said locking member when the post is fully received within said opening.

6. A clasp comprising a male part having a base and a post extending outwardly therefrom, a female part having an opening adapted to receive

said post, a hollow stud extending outwardly beyond said base, a locking member pivoted on said stud and adapted to swing from a position clearing said female part to a position overlying said female part, a spring disposed within said hollow stud and having one end engaging said locking member, a groove formed in said base, the other end of said spring being received in said groove and being anchored thereby, a bight formed on said second end of said spring and extending outwardly beyond said locking member to form a trigger, a catch formed on the outermost portion of said end of the spring and engaging said locking member, said catch being urged into engage-

ment therewith through the resiliency of said spring, said female part engaging said trigger, upon insertion of the post into said opening to release said locking member.
